E. G. LACOSTE.
ORTHOPEDIC CHAIR.

APPLICATION FILED NOV. 29, 1918.

1,325,252.

Patented Dec. 16, 1919.

Inventor
Eduardo Gabriel Lacoste,
By his Attorney *Henry P. J.*

UNITED STATES PATENT OFFICE.

EDUARDO GABRIEL LACOSTE, OF BUENOS AIRES, ARGENTINA.

ORTHOPEDIC CHAIR.

1,325,252.

Specification of Letters Patent.

Patented Dec. 16, 1919.

Application filed November 29, 1918. Serial No. 264,562.

To all whom it may concern:

Be it known that I, EDUARDO GABRIEL LACOSTE, a citizen of Argentina, residing at Calle Maipú 671, Buenos Aires, Argentina, have invented a new and useful Improvement in Orthopedic Chairs, of which the following is a specification.

My present invention relates to an orthopedic chair specially designed for the use of patients suffering from coxalgia and congenital luxation and a substantial feature of said chair consists in that it offers to the patient a maximum of comfort, allowing him to remain seated without causing any pain to the affected part of his body. As will hereinafter be seen, owing to the construction and general arrangement of the parts which constitute the chair and in particular, of its seat, which all have been devised to adapt themselves to the part affected by the above diseases, a perfect rest is obtained, while absolutely avoiding, owing to an instability of the seat, any movements liable to hurt the diseased part.

The chair comprises a pyramidal framing with a movable chair back, having integral lower extensions on which is supported the leg corresponding to the side affected by coxalgia. It further comprises two false or movable seats, to be used one or the other, according to the condition of the disease, said seats being arranged to actuate at different degrees of height, adjustable at will, and in combination with said movable chairback and with arm rests arranged to be raised. The framing is mounted on wheels and is suitably reinforced at its central part, in accordance with the size of the patient who is to use the chair. The front part of the chair, though provided with a shiftable cross stay, remains open, so that the invalid may sit down or rise without difficulty.

In order to facilitate a clear understanding of this specification, detailed drawings have been annexed thereto, in which:

Figure 1 shows a front elevation of an orthopedic chair constructed in accordance with this invention.

Fig. 2 represents a rear elevation of the same chair.

Fig. 3 is a lateral elevation which illustrates the movements of the chair back and arm rests.

Fig. 4 is a perspective of the special seat for double coxalgia and congenital luxation.

Fig. 5 is a perspective of a seat for right or left coxalgia as well as for the first stage of congenital luxation.

In said drawings, 1 indicates the four legs which form the main supporting frame or base of the chair, said legs being mounted on wheels 2 and connected together by means of the cross bars 3 and 4 of which the upper one 4, at the front, is adapted to be raised. In the case of chairs destined for adults, at the front an additional standard or fifth leg 5 may be arranged, in combination with the seat, so as to serve as a front support. The chair-back 6 is conveniently hinged to the rear cross bar 7 and carries, by means of the plates 8, suitably curved in order to clear the hinges, the hanging extensions or supports 9, whereon is to rest the leg of the invalid. The position of the chair-back and in consequence of the said supports, may be adjusted by shifting the point of engagement of the rod 10 with the toothed sectors 11, arranged one at each side. The arm rests 12 are hinged at their rear end, for the better comfort of the invalid. At the central part of the chair is conveniently mounted a pipe section 13, provided with a thumb screw 14. Said pipe 13 serves to support the seat and retain the same at the desired degree of height. Whichever of the seats shown in Figs. 4 and 5 be adopted, the same invariably comprises a rod 15, arranged to slide within the said pipe 13. The seat of Fig. 4, as has already been stated, is destined to be used in connection with congenital luxation; it consists of a central pad 16, formed after the manner of a bicycle seat, and two lateral pads 17, 17, which by means of compass joints 18, 18 may be set at different degrees of incline, as may be required by each particular case. The seat shown in Fig. 5 consists of two tiltable parts 19, secured by hinges to the central part 20, in combination with means which allow of retaining them in their horizontal position.

As already mentioned before, this seat has been specially devised for patients suffering from right or left coxalgia. On lowering one of the parts, a lateral opening is left in the seat which allows of the ready pas-

sage of the leg of the side where immobility is required. The seat in its horizontal position serves for the first stage of congenital luxation.

- 5 Fig. 1 illustrates the said seat, suitably arranged for use in connection with left coxalgia.

Up to this date, no orthopedic chair has been specially constructed for the treatment 10 of the above said diseases, in spite of the considerable number of persons suffering therefrom.

It will be understood therefore, that when referring to the chair shown in the drawings, this is done by way of example, since 15 the details of construction of the same may vary without altering the novelty of the invention. The essential features of this invention substantially reside in a chair, of 20 any suitable form of construction, comprising as principal parts a chair-back of adjustable incline, with lower extensions for the support of the legs, in combination with movable or fixed seats, comprising movable 25 parts, all of which permits of an efficient treatment of the afore mentioned diseases.

Having now particularly described and ascertained the nature of my said invention and in what manner the same is to be performed, I declare that what I claim, is:

- 30 1. An orthopedic chair, comprising, a sectional seat, leg supports extending below and adjustable with relation thereto, and means for rendering one of the sections of

the seat inoperative, whereby one of the leg supports is rendered operative.

2. An orthopedic chair comprising an adjustable seat, an adjustable back having leg supporting portions extending below the seat, and means for adjusting the seat where- 40 by the supports are accessible to the legs.

3. An orthopedic chair for invalids, comprising a seat having adjustable portions, a pivoted back having portions extending below the seat, and means for adjusting the 45 seat portions to permit access of the legs to the extending portions.

4. An orthopedic chair for invalids comprising a seat having lateral hinged portions, a pivoted back having leg supporting portions extending below the seat, means for inclining the back and leg supports, and means for angularly displacing said hinged portions. 50

5. An orthopedic chair for invalids comprising a seat having lateral hinged portions, means for raising and lowering the seat, a combined back and leg support pivoted behind the seat and extending above and below the latter, means for adjusting the inclination of said support, pivoted arm rests on either side of the seat, and means for angularly adjusting said lateral portions for the purpose specified. 55 60
